STANLEY MCCLATCHIE, OF BERLIN-WILMERSDORF, GERMANY

MAGNETIC PICK-UP DEVICE

Application filed December 7, 1929, Serial No. 412,490, and in Germany July 5, 1929.

This invention relates to magnetic pick-up devices, especially for use for reproducing sound from phonograph records.

Phonograph pick-ups as hitherto known, have the drawback that it is difficult to assemble, interchange and adjust individual parts. This is particularly objectionable in the case of the essential moving part of the pick-up, the armature with its associated damping means of rubber. As is well known, rubber rapidly loses its original elasticity, so that in the course of from four months to one year, the operation of the pick-up is markedly impaired.

It is the object of this invention to overcome the afore-mentioned drawbacks and to provide a sound-box which consists essentially of two parts, (1) a casing with the magnet, spool and pole-pieces, and (2) a readily detachable and adjustable supporting member for the armature with its rubber damping means.

A further object of my invention consists in providing simple clamping means for keeping the needle in its supporting element, which clamping means are arranged so as not to oscillate with the needle.

Further objects of the invention will become apparent from the following description taken in reference to the appended drawings and disclosing, by way of illustration, some practical forms of embodiment of the invention.

Referring to the drawings, Figure 1 shows a preferred form of pick-up in accordance with my invention, in a longitudinal section.

Figure 2 is a cross-section taken at right angles to the section of Figure 1.

Figure 3 is an enlarged cross-section of a detail of Figure 2, taken at the section-line A—B.

Figure 4 illustrates an alternative construction.

Figure 5 is a fragmentary section of a device as shown in Figure 4, but with modified means for holding the needle in an operating position.

Figure 6 is a bottom view of Figure 5.

Figure 7 shows, on an enlarged scale, the fastening of the spool flange to the separating

wall between the main casing and its detachable part, by means of eyelets, which, at the same time, serve as terminal connections for the coil.

Figures 8 and 9 show respectively, sections 55 taken on the section-lines A—B and C—D of Figure 4.

Similar reference numbers refer to similar elements throughout the different views of the drawings.

Referring to Figures 1 and 2, a magnet 1, which is preferably a permanent magnet and which may be rotated by means of a knob 2b, is mounted at the upper part of a casing 2, and 2a, with a resilient spacing member 3, placed between. The spool 4 has a flange 5, which is clamped, together with the pole-pieces 6 and the disc 7, between the two halves of the casing 2 and 2a. The casing is held together very simply by the screws 8 and 9, which are threaded into the loose bushings 10, 11. The disc 7 serves to prevent the rotatable magnet from sticking to the pole-pieces so as to cause undue friction.

The armature consists of an iron tube 12 75 surrounded by a rubber cushion 13, which is held by an inward tubular extension 14 of the supporting member 15. The upper part of the armature tube 12 is provided with indentations 16, which serve as a stop for the needle, which thus can only be inserted to a predetermined depth. The needle 17 is held in operating position in the armature 12 by means of a clamp 18, which, through the spring 19, exerts a pressure against the needle at the point which is the axis of oscillation. At this point, the clamp does not interfere with the needle's movement. The clamp has a press-button portion 20 and a tongue 21, which latter serves to force the needle into the wedge-shaped portion 12a of the armature 12. (See Figure 3.)

In the embodiment shown in Figures 4 and 7, the clamp consists of a bent elastic wire 21a, carried by the member 15 and having an outside extension through a slot of the casing. In this embodiment, the armature holder 15 is extended to form the cup-shaped lower casing portion, which in Figure 1, is the separate part 2a. The spool-flange 8 is 95 100

here secured to the casing 2 by the eyelets 22, shown on an enlarged scale in Figure 7.

In the embodiment, according to Figures 5 and 6, the pressure member for the needle 17 consists of a tongue 26 of a slider 18a, which is forced against the needle 17 through the action of a rubber cushion 23. When it is desired to exchange needles, it is merely necessary to depress the portion 20 of the slider 18a.

The detachable part 15 with associated armature system, is secured to the main casing by means of the set-screws 24 and 25. A resilient gasket 28 is interposed. The washer 27 of Figure 1 serves to strengthen the holder 15 where the screws force the holder against the gasket.

The various forms just described have, in common, that the armature system, with an associated supporting structure, is detachably and adjustably secured to the main body of the pick-up. Provision is thus made for readily renewing the armature system as soon as the rubber damping begins to deteriorate.

In practice, the dealer selling the device would carry in stock fresh armature systems for renewal. He has merely to remove the two set-screws 24 and 25 and attach a new system. The position of the armature between the pole pieces is readily adjusted by means of a phonograph needle inserted in one of the transverse holes shown in the screw 25. This adjustment may be carried out while the pick-up is actually playing, which makes the operation simple even for a layman, as he may thus gauge the correct adjustment by ear.

Furthermore, the interchange of needles is greatly facilitated by the use of a clamp, instead of a set-screw, as has heretofore been customary. This construction has the further advantage of relieving the armature of the undesirable additional weight of the set-screw with its associated threaded holder.

It is evident that my invention may be embodied in other forms and in other associations of elements than those here shown, and that the scope of the invention is not to be construed as limited to the particular structures and combinations described and illustrated.

What I claim is:—

1. A sound reproducing pick-up device for phonographs and the like, comprising, in combination, a main supporting structure, a detachable part of said structure, a phonograph needle to be subjected to mechanical oscillations corresponding to the oscillations of sound to be reproduced, a cushion of elastic material carried by said detachable part to simultaneously serve for holding said needle in operating position and acting as a dampening means for said mechanical oscillations.

2. In a sound reproducing pick-up device for phonographs and the like, comprising, in

combination, a main casing structure, a detachable part of said casing, an element subjected to mechanical vibrations corresponding to the vibrations of sound to be reproduced and a cushion member of elastic material carried by said detachable part to serve as a support of said element and as a dampening means of said mechanical vibrations. 70

3. In a sound reproducing pick-up device for phonographs and the like, comprising, in combination, a main casing structure, an operating magnet, a detachable part of said casing, a phonograph needle subjected to mechanical oscillations corresponding to oscillations of sound to be reproduced, a cushion member of elastic material carried by said detachable part, a magnetic armature cooperating with said magnet held by said cushion member and engaging said needle in a clamping position, whereby said cushion, 80 simultaneously serves as a pivotal support of said needle and as a dampening means of said mechanical oscillations. 85

4. In a sound reproducing pick-up device for phonographs and the like, comprising, in combination, a main casing, a detachable part of said casing, a magnet structure carried by said casing, a cushion member of elastic material carried by said detachable part, a phonograph needle to be subjected to mechanical oscillations corresponding to the oscillations of sound to be reproduced, a magnetic armature cooperating with said magnet, being held in a clamped position within said cushion member and engaging said 100 needle, said cushion serving as a support for said armature and as a means for dampening its oscillations. 95

5. In an electro-magnetic sound reproducing pick-up device for phonographs and the like, comprising, in combination, a main casing structure, a magnet carried by said structure, pole pieces of said magnet, a detachable part of said main structure, a phonograph needle to be subjected to mechanical oscillations corresponding to the oscillations of sound to be reproduced, a cushion of elastic material carried by said detachable part and arranged between said pole pieces, said needle being supported by said cushion, serving at the same time as a dampening member for said mechanical oscillations. 105

6. In an electro-magnetic sound reproducing pick-up device for phonographs and the like, comprising, in combination, a main casing structure, a magnet carried by said structure, pole pieces of said magnet, a detachable part of said structure, a phonograph needle to be subjected to mechanical oscillations corresponding to the oscillations of sound to be reproduced, a sleeve-like cushion of elastic material carried by said detachable part and arranged between said pole pieces, a sleeve-like magnetic armature held in a clamped position within said cushion and engaging 125 110 115 120 125 130

said needle, acting simultaneously as a dampening member for said mechanical oscillations and said needle also serving as operating armature of said pick-up device.

5 7. In an electro-magnetic sound reproducing pick-up device for phonographs and the like, comprising, in combination, a main casing structure, a magnet carried by said structure, pole pieces of said magnet, a detachable part of said structure, a rubber tube carried by said detachable part and arranged between said pole pieces, a phonograph needle to be subjected to mechanical oscillations corresponding to the oscillations of sound to be 10 reproduced, a metallic sleeve within said rubber tube to serve as operating armature of said pick-up device and holding said needle in operating position, said rubber tube simultaneously serving as a dampening member of said mechanical oscillations.

15 8. In a phonograph sound reproducing pick-up device, as described in claim 7, wherein in said detachable part is adjustably connected to said main structure by means of 20 intermediate layers of elastic material.

25 9. In an electro-magnetic sound reproducing pick-up device for phonographs and the like, comprising, in combination, a main casing structure, a magnet within said casing, a 30 detachable part of said structure, pole pieces of said magnet, a rubber tube element carried by a tubular extension of said detachable part and arranged between said pole pieces, a metallic sleeve within said rubber tube to 35 serve as operating armature of said pick-up device, a phonograph needle to be subjected to mechanical oscillations corresponding to the oscillations of sound to be reproduced, said needle being carried by said sleeve in 40 clamped position, whereby said rubber tube simultaneously serves to support said needle in operating position and to dampen said mechanical oscillations.

45 10. In a phonograph pick-up device, as described in claim 9, wherein said detachable part is adjustably connected to said main casing structure by means of intermediate elastic layers.

50 11. In an electro-magnetic sound reproducing pick-up device for phonographs and the like, comprising, in combination, a main casing structure, a magnet within said casing, a detachable part of said structure, pole pieces of said magnet, a rubber tube element carried 55 by a tubular extension of said detachable part and arranged between said pole pieces, a metallic sleeve within said rubber tube to serve as operating armature of said pick-up device, a phonograph needle subject to mechanical oscillations, being carried by said sleeve in operating position, whereby said rubber tube simultaneously serves to support said needle and to dampen its movements and a resilient pressure element for holding said 60 needle in said armature sleeve, said pressure 65

element being arranged to be movably mounted to apply its pressure to said needle and to hold it in its armature.

70 12. In an electro-magnetic phonograph pick-up device, as described in claim 11, in which said pressure element consists of a slider associated with said main casing provided with a slot for receiving needle armature and a spring member between said slider and said main casing pressing said needle 75 against the inside of its armature.

80 13. In an electro-magnetic sound reproducing pick-up device for phonographs and the like, comprising, in combination, a main casing structure, a magnet within said casing, a 85 detachable cup-shaped part of said structure, pole pieces of said magnet arranged within said detachable part, a rubber tube element carried by an inward tubular extension of said detachable part and arranged between 90 said pole pieces, a metallic sleeve within said rubber tube to serve as operating armature of said pick-up device, a phonograph needle to be subjected to mechanical oscillations corresponding to the oscillations of sound to be 95 reproduced, said needle being carried by said sleeve in operating position, whereby said rubber tube simultaneously serves as a pivotal support for said needle and as a dampening member of said mechanical oscillations 100 and a pressure element, together with a spring for holding said needle in said armature sleeve, said pressure element being arranged to be movably mounted against the action of said spring on said detachable part to apply its pressure to said needle and to hold it in its armature.

105 14. In an electro-magnetic phonograph pick-up device, as described in claim 13, in which said pressure element consists of a metal plate with a bent over part and an elastic member co-operating with said bent over part to exercise pressure of said needle to retain it in its position within said armature.

In testimony whereof I affix my signature.

STANLEY McCLATCHIE.
